United States Patent Office.

RODMAN BACKUS, OF ALBANY, NEW YORK.

Design No. 3,493, dated May 11, 1869.

DESIGN FOR THE PLATES OF A STOVE.

The Schedule referred to in these Letters Patent and making part of the specification.

To all whom it may concern:

Be it known that I, RODMAN BACKUS, of the city and county of Albany, in the State of New York, have originated a new Design for Stove-Plates, of which the following is a full, clear, and exact description, reference being had to the accompanying drawings, making part of this specification, in which—

Figure 1, sheet 1, is a front elevation of the stove to which my design is applicable.

Figure 2, sheet 2, is the upper section of my new design.

Figure 3 is the lower section.

Figure 4 is a top view of the top section.

Similar letters of reference indicate corresponding parts in the several figures.

The design which I have produced relates to the two outer walls, or sections which surround the fire-pot and the combustion-chamber of a fuel-magazine illuminating parlor-heater.

The drawings, fig. 1, represent such a heater with the two sections above referred to in their proper places, and figs. 2 and 3 represent these sections detached from other parts of the heater.

The novelty of the design consists in a polygonal ogee-ornament, G, resting upon and combined with a

polygonal ogee-section, B, through the facets *b*, of which, windows of an ornamental character are made. The base of this section B is contracted by a polygonal concave or cavetto.

The section A, which is arranged beneath the section B, is of the form of a polygonal cavetto, whose facets may or may not be perforated or reticulated, and this section is capped by a polygonal moulding of suitable design.

It will be seen that the many-sided cavetto-section A and the window-section B, with corresponding sides or facets, when taken together, present the outline of a double ogee, which is broken by an intermediate plain ogee, that ornaments the base of the Gothic windows in section B, and also the upper end of the cavetto-base A.

What I claim as my invention, and desire to secure by Letters Patent, is—

The design for stove-sections A and B, as described and shown.

RODMAN BACKUS.
